UNITED STATES PATENT OFFICE.

THOMAS E. POTTS, OF LOS ANGELES, CALIFORNIA, ASSIGNOR OF ONE-THIRD TO
PETER MADSEN AND ONE-THIRD TO MARTIN MADSEN, BOTH OF LOS ANGELES,
CALIFORNIA.

DISTILLATE-BURNER.

1,153,516.

Specification of Letters Patent. Patented Sept. 14, 1915.

Application filed November 9, 1914. Serial No. 871,212.

To all whom it may concern:

Be it known that I, THOMAS E. POTTS, a citizen of the United States, residing at Los Angeles, in the county of Los Angeles, State 5 of California, have invented a new and useful Distillate-Burner, of which the following is a specification.

The invention relates to distillate burners, such as are employed in ranges, furnaces, or 10 the like, these burners employing a relatively low grade of petroleum fuel, such as commonly called fuel oil or distillate, which is difficult to ignite and gasify but which when once gasified burns with an intense 15 flame and high efficiency.

It is desirable in such burners to provide means for preheating or vaporizing the fuel before it is passed to the flame, and the 20 principal object of the invention is to provide means for so vaporizing the fuel.

As such burners are used by unskilled labor and as they are subjected to great extremes of temperature, resulting in frequent 25 injury to certain parts thereof, it is highly desirable that they be made in a form that will be cheap to construct and that they may be installed so that damaged parts may be readily removed and replaced when desired, and a further object of the invention is to 30 provide a burner which will be of relatively few parts, these parts being low in first cost and easily replaced.

In distillate burners used in ranges a very 35 hot fire is required at times and a relatively slow fire is required at other times.

A further object of the invention is to provide a burner which may be utilized to produce an intense flame at times and in which the flame may be reduced when desired so 40 that the burner can be used for those purposes which do not require such an intense fire.

Further objects and advantages will be made evident hereinafter and will be evident to one skilled in the art from an examination of the annexed specification and the drawing which is made a part hereof.

In the drawing, which is for illustrative purposes only: Figure 1 is a cross section of 50 a range in which one of my inventions is installed. Fig. 2 is a front elevation of a portion of the range with the invention installed therein. Fig. 3 is a partial section on the plane X³—X³ of Fig. 1. Fig. 4 is a 55 cross section showing an alternative method

of installing my invention. Fig. 5 illustrates a damper which may be used in either form of my invention but which is shown in place in Fig. 4.

While I have illustrated my invention as 60 applied to a range I do not restrict myself to such an application, as a similar burner may be used in any place where liquid fuel can be used.

The invention as illustrated consists of a 65 primary pan 10 and a secondary pan 11. The primary pan 10 is cast in a single piece having a front lip 12 and a rear lip 13 and having side walls 14 and 15. A distillate supply pipe 16 is tapped into the front lip 70 12 and is supplied with distillate or other liquid fuel through a valve 17 from a pipe 18. The side walls 14 and 15 have ledges 19 formed thereon as illustrated in Fig. 3 and the secondary pan is formed of a heating 75 plate 20 having a front lip 21 and a rear lip 22 formed thereon, the heating plate 20 joining side walls 23 which extend downwardly and slide on the ledges 19 in the side walls 14 and 15 of the primary pan 10. A front 80 deflector 24 rests on the side walls 23 extending completely across the front of the burner and being provided with a draft lip 25 which extends downwardly over the heating plate 20. A cup 26 is formed on the deflector 24 and a small opening 27 extends from the bottom of the cup 26 into the lip 25 approximately as shown in Fig. 1. A distillate supply pipe 28 extends over the 85 cup 26 and is provided with a pet cock 29 by which the flow of distillate may be regulated, the distillate being dropped from this pet cock into the cup 26.

The above described parts are common 90 both to the form shown in Fig. 1 and the form shown in Fig. 4. In the form shown in Fig. 1 a rear deflector 30 is formed integral with the rear ends of the walls 23 and a loose deflector 31 is placed on top of the walls 23 extending completely across said walls and forming a tight joint with the deflector.

The method of operation of my invention 95 shown in Fig. 1 is as follows: The pet cock 29 being partially open, distillate, or other liquid fuel, is allowed to flow into the cup 26 and through the opening 27 into the secondary pan 11, overflowing into the primary pan 10 over the lip 22 which is slightly lower 100 than the lip 21. Fuel can also be fed into 105

the primary pan 10 through the pipes 16 and 18 and valve 17. The distillate is ignited in the lower pan, burning freely therein and heating the secondary pan 11, the flames 5 passing upwardly between the lip 22, the deflector 30, and the loose deflector 31, and from thence upwardly into the upper part of the range 32 and outwardly through the passage 33 into the flue. The fire in the primary pan heats the heating plate 20 so that the fuel which drips into the cup 26 from the pet cock 29 is vaporized as it falls from the opening 27 onto the hot plate 20. This heating and vaporization of the fuel results 10 in a very intense hot flame and a very complete combustion. The amount of such heating may be regulated by the valve 17 and after the fire has been fully established the burning of fuel in the primary pan 10 may often be dispensed with. The combustion 15 consists essentially of a double flame, due to the fact that the air for combustion passes over both the lips 21 and the lip 22 meeting just above the central part of the pan 11 and uniting with the gasified fuel to form an intense flame. It will be noted that the secondary pan 11 together with the front deflector 24 and the loose deflector 31 are not 20 rigidly connected to any portion of the stove, 25 being simply inserted and resting upon the pan 10. They may therefore be drawn out of the stove without detaching any fastenings and new parts may be inserted in case the intense heat has injured any portion of the 30 heater. The primary pan 10 being remote from the intense fire is not likely to be damaged and may be permanently installed in the range. I have found in practice that the loose deflector 31 being exposed to the 35 fire from all sides is very likely to become injured from the fire and I have therefore made it in a separate piece from the secondary pan 11 and the side walls 23. For convenience in casting the front deflector 40 45 is also so formed, simply resting upon the top of the side walls 23. Where the range is of suitable construction the embodiment of my invention illustrated in Fig. 4 will prove 50 very efficient. In this form of my invention the deflector 30 and the hood 31 are omitted, the side walls 23 being formed with rectangular ends and fitting against a body of fire brick 50 and under a projecting ledge of fire brick 51.

55 The method of operation of the embodiment shown in Fig. 4 is exactly the same as that shown in Fig. 1, the fire brick members 50 and 51 being substituted for the deflector 30 and the loose deflector 31 and serving exactly the same purpose. In practice the members 10, 11, 30, 31, and 24 are formed of moderately heavy cast iron, and I have found that they retain the heat and work 60 efficiently over wide ranges of fire temperature. In a range fire, or indeed in almost

any application for which the invention is suited, it is highly desirable at times to have a relatively less intense fire. For the purpose of regulating the fire the damper illustrated in Fig. 5 is used, this damper consisting 70 of a rectangular member 52 having a handle 53 formed thereon. The rectangular member 52 is of such a size that it fits into the forward opening between the primary pan 10 and the secondary pan 11, thus shutting off the draft which normally passes backwardly between the two pans and around over the lip 22. Projections 54 are provided on the member 52 so that it will be held in 75 the opening.

80 While the invention has been illustrated as applied to a hotel range it is evident that it could be applied to furnaces used for other purposes, the particular embodiment shown being chosen for illustrative purposes only. 85 Further, although the burner has been shown with the forward end projecting through the wall of a range it is evident that in the case of other furnaces it may be desired to place it entirely within the furnace, 90 and I wish it distinctly understood that such an application falls within the scope of my invention.

I claim as my invention:

1. A liquid fuel burner comprising a primary fuel pan, a secondary fuel pan having side walls resting on said primary pan and a heating plate extending across between said walls over said primary pan, means for directing the heated gases from said primary pan over the surface of said secondary pan, and independent means for supplying liquid fuel to each of said pans.

2. A liquid fuel burner comprising a primary pan, means for supplying fuel to said pan, side walls for said pan having ledges formed thereon, a secondary pan having secondary side walls adapted to rest on said ledges, a front deflector resting on said secondary side walls and so shaped that it directs an air current across the top of said secondary pan, a rear deflector resting on said secondary side walls and so shaped that it directs the current of air entering between said pans across the top of said secondary 110 pan, and means for supplying liquid fuel to said secondary pan.

3. A liquid fuel burner comprising a primary pan, means for supplying fuel to said pan, side walls for said pan having ledges 115 formed thereon, a secondary pan having secondary side walls adapted to rest on said ledges, a front deflector resting on said secondary side walls and so shaped that it directs an air current across the top of said secondary pan, a rear deflector resting on said secondary side walls and so shaped that it directs the current of air entering between said pans across the top of said secondary 125 pan, a cup formed on said front deflector, 130

said cup having an opening in the bottom thereof extending inwardly to a point over said secondary pan, and means for supplying fuel to said cup.

5 4. A liquid fuel burner comprising a primary pan, means for supplying fuel to said pan, side walls for said pan having ledges formed thereon, a secondary pan having secondary side walls adapted to rest on said ledges, a front deflector resting on said secondary side walls and so shaped that it directs an air current across the top of said secondary pan, a rear deflector resting on said secondary side walls and so shaped 15 that it directs the current of air entering between said pans across the top of said secondary pan, a damper for closing the air supply opening between the pans, and means for supplying liquid fuel to said secondary pan.

20 5. A liquid fuel burner comprising a primary fuel pan consisting of a flat plate with a surrounding edge, a similarly formed secondary fuel pan located above said primary fuel pan, and means for independently feeding fuel to each pan.

25 6. A liquid fuel burner comprising a primary fuel pan consisting of a flat plate with a surrounding edge, a similarly formed sec-

ondary fuel pan located above said primary 30 fuel pan, means for deflecting hot gases from the primary pan over the upper surface of the secondary pan, and means for independently feeding fuel to each pan.

7. A liquid fuel burner comprising a primary fuel pan consisting of a flat plate with a surrounding edge, a similarly formed secondary fuel pan located above said primary fuel pan, means for shutting off the supply 35 of air to said primary fuel pan, and means 40 for independently feeding fuel to each pan.

8. A liquid fuel burner comprising a primary fuel pan consisting of a flat plate with a surrounding edge, a similarly formed secondary fuel pan located above said primary 45 fuel pan, means for deflecting hot gases from the primary pan over the upper surface of the secondary pan, means for shutting off the supply of air to said primary fuel pan, and means for independently feeding fuel 50 to each pan.

In testimony whereof I have hereunto set my hand at Los Angeles, California, this 3rd day of November, 1914.

THOMAS E. POTTS.
